Inventor:

Ralph L. Winter.
Hans M. Isaacson,
Attorney.

UNITED STATES PATENT OFFICE.

RALPH L. WINTER, OF EAST DIXFIELD, MAINE.

TWINE CUTTER.

Application filed August 11, 1927. Serial No. 212,338.

This invention relates to cutting instruments and particularly to such instruments known as twine cutters.

One of the objects of this invention is a 5 twine cutter of exceedingly simple construction economical to manufacture.

Other objects and advantages will appear from the more detailed description set forth below taken in conjunction with the drawing, wherein there is shown by way of illustration in

Figure 1, a plan view of the cutter mounted in position; in

Figure 2, a front elevation of the structure of Figure 1; in

Figure 3, a section on the line 3—3 of Figure 2; and in

Figure 4, a section on the line 4—4 of Figure 2.

20 But while the drawing and more detailed description set forth disclose the preferred form of the invention, it will be understood that various changes may be made in that structure and arrangement by those skilled 25 in the art, without departing from the scope and spirit of this invention.

In the most desired form illustrated in the drawing, there is shown a substantially U-shaped frame 1 having the arms 2, 3. 30 Such frame may be made of any desired material, although thin sheet metal pressed into the desired shape has been found advantageous. One of the arms of the U, is desirably enlarged, as shown at 4, to provide 35 a base by means of which the cutter may be rigidly attached to a support 5. For such purposes the enlarged portion 4 is desirably provided with perforations through which screws 6, 6 may be inserted. The arms of 40 the U are also desirably provided with alined perforations 7, 7 for the reception

of a split rivet 8, having arms 9, 9 providing a channel 10 therebetween. A cutting blade 11 having a cutting edge 12 is inserted within the arms of the U through the channel 10, the rivet 8 serving to hold the blade 11 rigidly within the arms of the U. The 45 blade 11 is preferably shaped as shown so that on its inner edges it fits against the inner face of the U-shaped frame member. 50

The structure shown consists of a minimum number of parts which may be readily assembled. The desired frame member 1 having been made, the blade 11 is inserted into position, the split rivet 8 is then inserted through the perforations and the lower end of the rivet swaged so that the arms of the U-shaped frame hold the cutting 55 blade rigidly in position.

The blade 11 is preferably formed of hard 60 steel, but this element as well as the frame, may be made of any desired material. Preferably the frame member should have some flexibility.

The cutter is desirably mounted on a 65 table, shelf or other desired article 5, and due to the exposed downwardly extending cutting edge 12 readily serves to cut cord, twine, etc., drawn against the cutting edge.

Having thus set forth my invention, I 70 claim:

A twine cutter consisting of a substantially U-shaped frame member having alined perforations in the arms of the U adapted to receive a rivet, a cutting blade 75 placed within said frame member, the rivet being split and passing about said blade through the aforesaid perforations, tying the arms of the U together against the inner edges of the cutting blade.

RALPH L. WINTER.
